UNITED STATES PATENT OFFICE.

JULES LÉON BON, OF PARIS, FRANCE.

APPARATUS FOR RAISING AND LOWERING SHUTTERS, BLINDS, OR CURTAINS.

Application filed May 27, 1920. Serial No. 384,709.

To all whom it may concern:

Be it known that I, JULES LÉON BON, citizen of the French Republic, residing at 34 Boulevard Haussmann, Paris, France, have invented new and useful Improvements in Apparatus for Raising and Lowering Shutters, Blinds, or Curtains, of which the following is a specification.

This invention relates to the kind of apparatus employed for raising and lowering shutters, blinds and curtains that are wound on a drum and are moved in front of a window, a door or other opening and in which the working of the said apparatus is effected from inside the house or apartment. It relates likewise to that kind of apparatus in which the shaft or spindle of the drum on which the shutter, blind or curtain is wound, is mounted in a barrel containing a spiral spring which facilitates the winding up of the shutter, blind or curtain.

The main characteristic of the apparatus which forms the object of the present invention resides in the fact that it can be mounted either on the right or on the left of a window or other opening.

In the accompanying drawing:

Fig. 1 shows a front elevation of this apparatus as seen from the side opposite to that which is intended to be fixed against the wall, the cover of the casing containing the toothed sectors having been partly removed. In this figure, the apparatus is shown applied on the right side of an opening.

Fig. 2 shows a front elevation of the same apparatus applied to the left side of an opening.

Fig. 3 shows a bottom plan of this apparatus applied as in Fig. 2.

Fig. 4 shows the apparatus, the cap keeping in position the various juxtaposed members having been removed for the sake of more clearness, the pinion mounted on the barrel meshing with the smaller toothed sector. This corresponds to the moment when the blind or shutter is being lowered.

Fig. 5 is a similar view of the apparatus, the pinion mounted on the barrel meshing with the larger toothed sector. This corresponds to the moment when the blind or shutter is being raised.

Figure 6 is a front and edge view of the forked arm which serves to bend or release

the braking spring wound on the barrel 55 casing.

Figure 7 is a longitudinal elevation of the actuating mechanism contained in the side casing of extension C' of the apparatus as disclosed in Figure 1, the front plate of said casing being removed for the sake of clearness.

Figure 8 is a transverse elevation of same, looking to the right on Figure 7.

According to the present invention, the 65 apparatus is constituted by: a rectangular fixing plate A with round corners, a cylindrical drum or barrel B containing a spiral spring not shown mounted on the said plate A; an oscillating plate C cut out in its central part provided laterally with a casing 70 C' containing the mechanism for actuating the apparatus and a cap D that keeps in position the various juxtaposed pieces.

The rectangular plate A is secured against 75 the vertical upright of a door-frame or window-frame by means of bolts that are screwed into holes 1 and 2 in such a way that the axis of the drum on which the shutter, blind or curtain is wound coincides with 80 the axis of the shaft 3 of the pinion 4, the latter being integral with the central part of the drum B.

Around the cylindrical drum or barrel B, a steel ribbon 5 is wound; its ends are attached by means of screws 6 to the cylindrical wall of a drum 7 which can oscillate on the fixed pin 8 secured to the plate A. This drum 7 is provided with a radially extending arm or rod 9, to which is pivotally attached 85 the lever 11 by means of the pin 10 secured to said lever adjacent one end thereof. The opposite end of said lever is enlarged and bifurcated to provide the forked head 12. The latter oscillates on a pivot 13 which is 90 fixedly secured to the plate A. A spiral spring 14 is secured at one end to a pin 10^a projecting from the face of the lever 11, and at its opposite end the said spring is secured by means of a pin 14^a to a post 15 100 fixed to the plate A. This arrangement permits the forked head 12 to slide on the pivot 13, thus enabling the steel ribbon 5 to be flexed more or less on the barrel B to vary the braking action on said barrel, accordingly as the rod or arm 9 is moved up or down to turn the drum 7.

The spring 14 constantly keeps the blade

or sheet ribbon 5 bent against the barrel B; consequently, it exerts a braking action on the spiral spring not shown contained in the barrel B, thus preventing the pinion 4 from rotating.

The oscillating plate C is formed adjacent one edge with a circular opening 16 adapted to snugly receive circular projection 16^a on the forked head 12 of the lever 11; this plate C is cut out at 17 in its central part. Opposite this cut out part of the said plate two toothed sectors 18 and 19 can move concentrically, the centre of these sectors being the axis of the circular projection 16^a of the lever 11 fitting the opening 16. These toothed sectors are provided with small connecting links 20 secured on the one hand to the plate C and, on the other hand, to the said sectors 18 and 19. The one or the other of the latter meshes with the pinion 4 and is thus actuated by the spiral spring contained in the barrel B. Extending from the edge of the oscillating plate C opposite that edge near which the opening 16 is formed is a casing C' which is somewhat thicker than the body of the plate C. In that casing C' independent oscillating finger-shaped levers 22, 23 both mounted on the axis 21 are provided which are respectively connected through connecting links 24, 25 with the toothed sectors 18, 19.

Close to the hollowed-out ends of the fingers 22, 23 an ogive-shaped cam 26 bears; this cam is mounted on the extremity of a rod 27 passing through a ring 28 provided with two bearings 29 which pivot in the side walls of casing C', only one wall being shown in Figure 1. In the forked end of the rod 27, the flat part 30 of the controlling rod 31 is thrust and fixed by means of a screw 32. The rod 31 which may be more or less long is furnished with a handle or lever, not shown. Springs 33 constantly force the fingers 22, 23 to press against the periphery of the cam 26.

In order to lower the shutter, blind, or the like the pinion 4, meshing with the toothed sector 18 (see Fig. 4) all that is necessary is to pull the rod 31 down; as the oscillating plate C is pivoted on the fixed pinion 4, owing to its meshing with the toothed sector 18, said plate C will force the forked head 12 upwardly, said head sliding on the pin 13. The arm 11 being thus raised carries upwardly the rod 9 thus rotating the drum 7 in a direction to release the brake-band 5 from braking engagement with the barrel B. The pinion 4 is then free to rotate in the direction shown by the arrow (Fig. 4) and moves the toothed sector 18 until such sector has reached the bottom end of its course. If it is desired to further rotate the pinion 4, it is only necessary to push the rod 31 upward; in such a

motion, as the arm 11 is no longer forced upwards, the brake-band 5 exerts a braking action on the barrel and thus stops the pinion 4. The toothed sector 18 rolling on the teeth of the stationary pinion then comes back to its original position. At this moment, if one pulls the rod 31 down, the same movements take place, thus causing the pinion to rotate and the shutter, blind or the like to be lowered.

If now it is desired to raise the shutter (Fig. 1) the rod 31 is turned to the extent of 180°; in such a rotation, the cam 26 moves the fingers 22 and 23 and the connecting rods 24 and 25, thus moving the toothed sector 18 away from the pinion and causing the toothed sector 19 to mesh with the pinion 4 (Fig. 5). If now up and down motions are imparted to the rod 31, the above described motions of the pinion 4 and sector 18 take place between said pinion and the sector 19 (Fig. 5).

When the rod 31 has reached its uppermost position, either the sector 18 or the sector 19 meshing with the pinion 4 acts as a catch and, completing the braking action, insures the absolute stoppage of the barrel B.

When it is desired to shift the position occupied by the apparatus from the right side (Fig. 1) unto the left side (Fig. 2), it is only necessary to cause the fixing plate A to turn to the extent of 180° in order that the pins 8 and 8^a be moved from the right to the left side; this being effected, the drum 7 is released from the said pin 8 and thrust on the other pin 8^a. The extremities of the brake band 5 pressing round the barrel B are then fixed to the screws 6 of the drum and the rod 9 is connected with the lever 11, the spring 14 having first been tightened and attached to the post 15^a symmetrically placed in relation to the post 15. The oscillating plate C is then juxtaposed upon the barrel B so that its casing C' is placed on the left side of the apparatus and its toothed sector 18 engages the pinion 4; the whole is finally firmly kept in position by means of the cap D which is laid and fixed on the top of the columns 15 and 15^a.

This apparatus while especially intended to be applied to shutters, blinds or curtains may also be utilized as a closing and locking device for metal curtains used to protect shop-windows and the like. In fact, when it has been completely lowered, it is not reversible as it cannot be raised from outside; it thus securely closes and locks the opening before which it is placed without the use of a locking pin or padlock.

What I claim and desire to secure by Letters Patent is:

1. Apparatus for raising shutters, blinds, or curtains, comprising a plate for attachment to a support such as a window or door

casing, a spring actuated drum mounted on said plate for rotation, a pinion fixed to said drum, a braking band extending around the periphery of said drum, a lever pivotally mounted on said plate and having a drum concentric with its pivot and to which drum the ends of said braking band are attached, a lever pivotally connected to the first named lever, and having a forked head, a pivot pin projecting from said plate and engaging in the forked head of said lever, a spring exerting its tension on said levers to cause the last named drum to turn sufficiently to flex the brake band, an oscillating plate pivotally mounted on said forked head, spaced sector gears, on opposite sides of said pinion, links pivotally attached to said sector gears and said oscillating plate, a pair of cam levers pivotally mounted on said oscillating plate, links connecting said cam levers to said sector gears, a lever pivotally mounted on said oscillating plate and having a cam to operate said cam levers, and springs to press said cam levers against said cam.

2. Apparatus for raising shutters, blinds, or curtains, comprising a plate for attachment to a support such as a window or door casing, a spring actuated drum mounted on

said plate for rotation, a pinion fixed to said drum, a braking band extending around the periphery of said drum, a lever pivotally mounted on said plate and having a drum concentric with its pivot and to which drum the ends of said braking band are attached, a lever pivotally connected to the said first named lever, and having a forked head, a pivot pin projecting from said plate and engaging in the forked head of said lever, a spring exerting its tension on said levers to cause the last named drum to turn sufficiently to flex the brake band, an oscillating plate pivotally mounted on said forked head, spaced sector gears on opposite sides of said pinion, links pivotally attached to said sector gears and said oscillating plate, a pair of cam levers pivotally mounted on said oscillating plate, links connecting said cam levers to said sector gears, a lever pivotally mounted on said oscillating plate and having a cam to operate said cam levers, springs to press said cam levers against said cam, said oscillating plate having a casing in which said cam levers and said operating cam lever are mounted.

In testimony whereof I have signed my name to this specification.

JULES LÉON BON.
